UNITED STATES PATENT OFFICE.

WILLIAM E. WHITE, OF CHICAGO, ILLINOIS, ASSIGNOR TO KALMAN STEEL COMPANY, OF CHICAGO, ILLINOIS, A CORPORATION OF DELAWARE.

GAUGE AND SUPPORT FOR BARS.

Application filed November 4, 1925. Serial No. 66,750.

My invention relates to supporting and spacing devices for concrete reinforcing elements, and has particularly to do with devices for use in connection with the construction of concrete roadways.

An essential element of the devices illustrated herein is a supporting member having a foot or base adapted to rest on the soil, the upper end being in abutting engagement with a bar or bar supporting element. The supporting member is arranged in cooperative relation to a stake or prong adapted to enter the soil, the body of the supporting member is bowed or curved inwardly into engagement with a portion of the stake or pin. By reason of this arrangement, an extremely firm frictional engagement is secured between the cooperating parts, such engagement being necessary in order to prevent accidental separation of the parts in handling and shipping.

As a further important element, I provide in connection with the stake, a lateral arm having the double function of spacing the device from the side form and of enclosing and retaining the bar in its correct position.

The device will be more readily understood by reference to the accompanying drawings, in which;

Fig. 1 is a sectional view through a portion of a roadway in which my improved device has been incorporated;

Fig. 2 is a plan view thereof before the concrete is poured;

Fig. 3 is an enlarged perspective view of my improved device;

Fig. 4 is a side elevation of a slightly modified form in which arrangement is made for supporting two bars in vertical alignment;

Fig. 5 is a similar view showing means for supporting two bars in horizontal alignment;

Fig. 6 is a side view of the construction shown in Fig. 5;

Fig. 7 is a front view of a further modification;

Fig. 8 is an edge view thereof;

Fig. 9 is a front view of a still further modification, and

Fig. 10 is an edge view thereof.

In the drawings, and referring particu-

larly to Figs. 1 to 3, inclusive, it will be seen that I provide a supporting member having a foot, 10, inwardly curved body 11, and an upper end, 12, terminating in a right angle extension, 13, having an open side notch, 14, therein. The parts, 10, 12, of the member are parallel and are apertured to accommodate the prong, 15, of a round wire spacing element, the lower end of which is adapted to enter the ground as shown in Fig. 1. The upper end, 16, of the stake is bent to a right angle and the arm acts as a spacer or gauge to determine the location of the bar, 17, relative to the side form, 18. The right angle bend in the wire stake provides for the driving of the stake into the ground if the soil is hard, the blow being applied at the angle. It will be noted that the arm, 15, is in register with the notch, 14, and, due to the round cross section of the prong or stake, it may be rotated in the apertures in the supporting member; in other words, it may be swung into the dotted line position of Fig. 2 to permit of insertion of the bar, 17. Thereafter it is returned to the full line position and the bar is securely confined within the seat provided at the upper end of the support.

The purpose of the inwardly curved body of the support is to provide for a firm frictional holding or clutching engagement between the edges of the apertures and the stake and by forming the supporting element of relatively stiff, resilient material, the parts may be very firmly held in a desired position. Of course, there is no possibility of disengagement after having been installed in operative position, but in order to avoid disengagement during handling and shipping, such provision is not only desirable but essential. The broad foot, 10, provides for an efficient stop or support for the superimposed weight and this insures an accurate gauge for the vertical position of the bar while the lateral arm, 16, insures accurate lateral positioning.

In the modification shown in Fig. 4, all of the parts heretofore described are identical in every particular. I have, however, provided for the support of a second reinforcing rod, 19, in vertical alignment with the rod, 17. This is accomplished by providing a supplemental supporting member

having a foot, 20, a vertical body, 21, and an upper end, 22. The terminal portion, 23, of the end is bent upward to form a seat for the bar. The portions, 20, 22, are apertured to receive the stake, 15, and the supplemental supporting element is firmly held by engagement with the foot, 10 and the bowed body, 11 of the main support.

In the construction of Fig. 5, the stake, 10 15 is unchanged and the supporting element is similar, comprising a foot, 24, a bowed body, 25, an upper end, 26, the terminal portion 27, of which extends upwardly, then laterally and downwardly to form second 15 bar seat, 28. The terminal portion, 29, of this seat is likewise notched to receive the lateral arm, 16, of the stake. This construction provides for the support of two reinforcing bars in horizontal alignment.

20 In the construction of Figs. 7 and 8, a stake 30 is utilized having an eye, 31 in its upper end for supporting a bar, 32. At an intermediate point in the length of the stake, I provide an offset 33, acting as a stop for 25 the supporting member of depth gauge. This member has a foot, 34 a bowed body, portion, 35, and a lateral upper end, 36, the parts, 34, 36, being apertured to accommodate the stake. The same principle is employed as heretofore described and the parts 30 are firmly held by frictional engagement.

In the construction of Figs. 9 and 10, the stake 37 is straight throughout its body portion, having an eye 38 in its upper end for 35 supporting a bar, 39. The depth gauge is the same as that heretofore described, except that it is of greater height, the abutment being between the upper end, 40 of the gauge and the eye. The same foot, 41, and 40 bowed body, 42, are utilized with the described advantages.

Obviously the construction is capable of other modifications than those shown and I do not wish to be limited except as indicated 45 in the appended claims:

1. In a device of the class described, the combination of a stake and a stop member, said stop member having a bowed body and laterally projecting apertured ends adapted 50 to receive said stake, the bowed body being in contact with said stake.

2. In a device of the class described, the combination of a round stake adapted to be driven into the soil and a stop member for 55 limiting the entrance of the stake into the soil, said stop member having a body and apertured ends for the reception of said stake, the body portion being inwardly deflected between its ends and in contact with said stake.

3. In a device of the class described, the combination of a round stake adapted to be driven into the soil and a stop member for 60 limiting the entrance of the stake into the soil, said stop member having a body

and apertured ends for the reception of said stake, and a horizontally disposed arm secured to said stake at its upper end and acting as a lateral spacer.

4. In a device of the class described, the combination of a round stake adapted to be driven into the soil and a stop member for 70 limiting the entrance of the stake into the soil, said stop member having a body and apertured ends for the reception of said 75 stake, the upper end of said stop member providing a seat for a reinforcing bar.

5. In a device of the class described, the combination of a round stake adapted to be driven into the soil and a stop member for 80 limiting the entrance of the stake into the soil, said stop member having a body and apertured ends for the reception of said stake, and a horizontally disposed arm secured to said stake at its upper end and acting as a lateral spacer, the upper lateral extension on said spacing member providing 85 a seat for a reinforcing bar.

6. In a device of the class described, the combination of a round stake adapted to be driven into the soil and a stop member for 90 limiting the entrance of the stake into the soil, said stop member having a body and apertured ends for the reception of said stake, a horizontally disposed arm secured 95 to said stake at its upper end and acting as a lateral spacer, the upper lateral extension on said spacing member providing a seat for a reinforcing bar, the spacing element of the stake being movable relative to the stop 100 member in order to open and close the seat for the reception of said bar.

7. In combination, a stake, the lower prong of which is adapted to enter the soil and the upper end of which is angularly disposed to act as a lateral spacer, and a stop member having a horizontal foot, a bowed body and a lateral extension at the upper end providing a seat for a reinforcing bar, the foot and lateral extension being apertured to receive the stake, the bowed portion being in contact with the stake, the angular extension of the stake lying over the bar seat.

8. In combination a stake having a vertical prong and a horizontal extension, a stop member having a bowed body and angular ends, the lower end portion acting as a foot and the upper end portion being depressed to form a bar seat, the angular extension being apertured to accommodate the prongs and said horizontal portion of the stake overlying the bar seat, the terminal portion of the bar seat being supported on the horizontal portion of the stake.

9. In combination, a stake having a vertical prong and a horizontal extension, a stop member having a bowed body and angular ends, the lower end portion acting as a foot and the upper end portion being de- 130

pressed to form a bar seat, the angular extension being apertured to accommodate the prongs and said horizontal portion of the stake overlying the bar seat, the terminal portion of the bar seat being supported on the horizontal portion of the stake, and said horizontal portion being adapted for rotation.

tion out of engagement with the terminal portion of the bar seat to open said seat for the reception of a bar.

10

In testimony whereof I have affixed my signature.

WILLIAM E. WHITE.
